PRESSER BAR VIBRATING DEVICE FOR
DARNINGCharles E. Colegrave, Lakewood, Ohio, assignor
to Sears, Roebuck and Company, Chicago, Ill., a
corporation of New York

Application May 18, 1944, Serial No. 536,066

7 Claims. (Cl. 112—236)

This invention relates to a sewing machine and more particularly to an arrangement whereby the presser bar and presser foot thereof can be adapted for ordinary sewing operations or for darning operations.

The invention may be used in sewing machines of the general type of that shown in the Hohmann et al. Patent No. 2,247,379, July 1, 1941. A sewing machine of this type is convertible from a condition wherein the machine is adapted for plain sewing to one wherein it is adapted for darning. This type of sewing machine employs a flat work bed for ordinary sewing operations and a cylindrical arm which supports the work when the machine is used for darning.

An object of the invention is to provide in a sewing machine a presser bar mechanism which can be adapted readily for either ordinary sewing operations or for darning operations, and which mechanism is simple in construction and efficient in operation.

Another object of the invention is to provide in a presser bar mechanism an actuating means for the presser bar and which means can be adjusted readily and easily to or from a position for ordinary sewing operations wherein it is inactive or from or to a plurality of active positions for darning operations and wherein endwise vibrating strokes of the desired amplitude may be imparted to the presser bar, in accordance with the thickness of the material being darned.

Further and additional objects and advantages of the invention will become apparent during the detailed descriptions of several embodiments thereof which are to follow.

Referring to the accompanying drawings,

Fig. 1 is an end elevational view looking at the free end of the horizontal portion of an arm bracket of a sewing machine and in which is employed a presser bar mechanism embodying the present invention, the actuating means for the presser bar being shown in inactive position.

Fig. 2 is a view partly in section and partly in elevation, with the section taken substantially on line 2—2 of Fig. 1 looking in the direction of the arrows, while the elevation is taken looking from the right of Fig. 1.

Fig. 3 is a fragmentary view similar to Fig. 1 but showing the actuating means for the presser bar adjusted to an active position and wherein it imparts lift to the presser bar between successive strokes of the needle bar.

Fig. 4 is a fragmentary view similar to Fig. 1 but shows a modified form of presser bar mech-

anism embodying the invention from that shown in Figs. 1 to 3 inclusive.

Fig. 5 is a fragmentary view similar to Fig. 4 but shows the actuating means for the presser bar of Fig. 4 adjusted to an active position wherein it imparts lifting movement to the presser bar between successive strokes of the needle bar, and

Fig. 6 is a sectional view taken substantially on line 6—6 of Fig. 5 looking in the direction of the arrows.

Referring to Figs. 1 and 2, the work plate or work bed of the sewing machine is indicated at 10 and said plate or bed is used for ordinary sewing operations. When the machine is used for darning operations the plate or work bed 10 is removed and a cylinder arm 11 is employed to support the work as is well understood in the art and as is clearly disclosed in said Hohmann et al. Patent No. 2,247,379.

20 The horizontal portion of the sewing machine arm bracket is indicated at 12 and said portion rotatably supports the main or needle bar shaft 13 which may be driven by any suitable means well understood in the sewing machine art and 25 forming no part of the present invention. The free end of the horizontal portion 12 of the sewing machine arm bracket reciprocatingly supports the vertically disposed needle bar 14, as is common in the art, and said needle bar has detachably 30 connected to its lower end, in the usual way, a needle 15.

The needle bar 14 is operatively connected to the needle bar shaft 13 by means of a pivoted link 16 which is pivotally connected to a crank arm 17, in turn, pivoted to a crank disk 18 fixed to the end of the needle bar shaft 13, as is well understood in the art. The usual tension device 19 and the customary take-up mechanism 20 are provided on the free end of the horizontal portion 12 of the arm bracket but form no part of the present invention. It will be understood that as the needle bar shaft 13 rotates, reciprocating movement will be imparted to the needle bar 14 and the needle 15 carried thereby, to cause the latter to pass through and out of the work during the sewing operation.

40 The free end of the horizontal portion 12 of the arm bracket also slidably supports the vertically disposed presser bar 21 which, at its lower end, carries a presser foot 22 which engages the work and is provided with a slot through which the needle 15 passes as it reciprocates. The presser bar 21 and presser foot 22 are held normally in their downward position under spring tension by means of a coil spring 23 which sur-

rounds the presser bar and has its upper end abutting against a threaded adjusting nut 24 whereby the tension of the spring can be varied. The lower end of the coil spring 23 abuts the upper side of a presser bar block 25 that is secured to the presser bar and extends into a slot formed in the arm bracket. A pivoted cam lever 26 is carried by the arm bracket and said lever can be moved from its lower inactive position as shown in Fig. 1 to its upper active position wherein it has engaged the block 25 to raise and hold the latter and the presser bar 21 and presser foot 22 upwardly against the action of the spring 23. The structure so far described is well known and will be fully understood by those skilled in the art.

As already stated, in ordinary sewing operations the presser foot 22 is held engaged with the work under tension of the spring 23 during the entire sewing operation. However, when the sewing machine is used for darning and similar operations it is necessary to impart a lifting movement to the presser foot between successive needle strokes in order that the work can be shifted on its support. The amplitude of the upward lifting movements imparted to the presser foot and presser bar will be varied in accordance with the thickness of the work upon which the darning operations are being performed. As for example, if thin socks or stockings are being darned, only a slight upward lifting movement need be given to the presser foot and presser bar, while on the other hand if the darning operations are taking place on blankets or other thick material a much greater upward lifting movement must be imparted to the presser foot 22 and the presser bar. The present invention is directed to an improved actuating means for imparting the upward lift movements to the presser bar and presser foot for darning operations. This actuating means can be adjusted to an inactive position for normal sewing operations or it can be adjusted to any one of a number of active positions for darning operations; the particular adjustment to active position which is given to the actuating means depending upon the thickness of the material to be operated on and the desired or necessary amplitude of the upward lifting movement required for the presser foot and the presser bar.

The needle bar 14 is provided with a roller 27 which when the actuating means for the presser bar is in inactive position performs no function. The actuating means for the presser bar which cooperates with the roller 27 when said means is adjusted to an active position, comprises in this instance a bell crank lever formed of the upwardly extending arm 28 and the substantially horizontally extending arm 29. The said bell crank lever is pivoted at the junction of the arms 28 and 29 on an eccentric pin 30 carried by one end of a shaft 31 that is rockably mounted in the horizontal portion of the arm bracket and extends therethrough at right angles to the needle bar 14. The upper end of the arm 28 of the bell crank lever is provided with a curved surface 28a which when the bell crank is in the inactive position shown in Fig. 1 does not contact with the roller 27 carried by the needle bar during the reciprocation of said bar. The outer or free end 70 of the substantially horizontal arm 29 of the bell crank lever is provided on its under side with a rounded downwardly extending projection 29a that engages a shoulder of the arm bracket when the bell crank lever is in the inactive position 75

shown in Fig. 1, wherefore the bell crank lever is maintained in its proper inactive position by the positive engagement of the projection 29a with the shoulder. The free or outer end of the arm 29 of the bell crank lever is provided on its upper side with an upwardly extending rounded projection 29b which when the bell crank lever is in inactive position as shown in Fig. 1 is spaced below the lower edge of the block 25 when the latter is in its lowermost position.

It will be noted that when the shaft 31 is rocked in a counterclockwise direction as viewed in Fig. 1, the pivotal axis for the bell crank lever is raised and shifted toward the left as viewed in Fig. 1 and that such raising and shifting of the pivotal axis of the lever moves the curved portion 28a of the arm 28 thereof into the path of movement of the roller 27 carried by the needle bar as said roller travels with the needle bar from its lowermost position to its uppermost position as shown in Fig. 3. It will be apparent that when the curved surface 28a of the arm 28 of the bell crank lever is contacted by the roller 27 during upward movement of the needle bar 14 said roller will move the arm 28 and rock the bell crank lever in a clockwise direction about its pivot, with the result that the arm 29 will swing upwardly causing the upward projection 29b thereof to engage the block 25 and raise the presser bar 21 and presser foot 22 against the action of the spring 23. The amplitude of the rocking movement imparted to the bell crank lever by the upward movement of the roller 27 depends upon the adjusted position of the pivotal axis of said lever and can vary between a minimum rocking movement and a maximum rocking movement. Of course the amplitude of the rocking movement imparted to the bell crank lever determines the amplitude of the upward lift movement imparted to the presser bar 21 and the presser foot 22 and should be correlated to the thickness of the material upon which the darning operation is taking place.

The shaft 31 is rocked from the position wherein the bell crank lever is inactive to a position wherein the bell crank lever is active by means of an operating handle 32 fixed to the right hand end of the shaft 31 as viewed in Fig. 2. Various suitable means may be employed for holding the shaft 31 and the handle 32 in any position to which they have been rocked and in the present illustration there is shown for this purpose a bowed spring 33 interposed between the handle 32 and the arm bracket. In Fig. 1 the handle 32 is shown as extending substantially horizontal when the bell crank lever is in inactive position, while in Fig. 3 the handle 32 is shown as having been moved from the inactive horizontal position to an active downwardly inclined position.

Referring more specifically to Fig. 3, it will be observed that the roller 27 is in engagement with the curved surface 28a of the arm 28 of the bell crank lever as it moves upwardly with the needle bar 14 and that such engagement will rock the bell crank lever in a clockwise direction to cause the projection 29b of the arm 29 thereof to press upwardly on the block 25 and lift the presser bar against the action of the spring 23. When the needle bar 14 moves downwardly the spring 23 will force the presser bar downwardly and will rock the bell crank lever in an anti-clockwise direction as viewed in Fig. 3. Hence, it will be seen that each time the needle bar 14 and needle 15 are moved upwardly the bell crank lever is rocked and the presser bar 21 and presser

foot 22 elevated, at which time the work may be shifted. It will also be seen that the amplitude of the lifting movement imparted to the presser bar and presser foot may be varied in accordance with the shifting adjustment imparted to the eccentric pin 39 by the rocking of the shaft 31 and handle 32.

From the foregoing description it will be evident that a simple and accurate actuating means is provided for the presser bar whereby during normal sewing operations said means can be rendered inactive while for darning operations the same means can be adjusted to any one of a number of different active positions correlated to the thickness of the material upon which the operation is being performed. The arrangement for effecting these adjustments of the actuating means possesses the advantageous attribute of simplicity as compared to the more or less complicated arrangements heretofore used for this purpose.

In Figs. 4 to 6 inclusive there is illustrated a modified form of actuating means for the presser bar 21 which differs somewhat from the form previously described. In this modified form the needle bar 14, presser bar 21, presser bar block 25, spring 23 and roller 27 on the needle bar, are identified by the same reference characters as in the previously described form, inasmuch as they are substantially identical therewith. The adjusting shaft 34 for the actuating means in this modified form is rockably supported in the arm bracket 12 in a manner similar to the adjusting shaft 31 of the first described form.

The shaft 34 adjacent its left hand end, as viewed in Fig. 6, has an arm 35 freely rockably supported on the shaft concentrically to the shaft axis and there is secured to the arm 35 a lever arm 36 which has its inner side curved as indicated at 36a for cooperation with the roller 27 as will later be explained. The arm 35 and the lever arm 36 could be formed of a single piece of material, but for purposes of assembly and to simplify the manufacture thereof the same are shown as formed of separate pieces which are suitably secured together. A coil spring 37 abuts against the outer or right hand side of the arms 35 and 36 and against the interior of the arm bracket 12; said spring being supported in proper position by a pin 38 and acting at all times to urge the arms 35 and 36 toward the roller 27.

The left hand end of the shaft 34 is provided with an eccentric pin 39 on which is rockably mounted a lever arm 40, the free end of which is provided on its upper side with a curved protuberance 40a adapted to engage the presser bar block 25 when the actuating mechanism is in its active adjusted position. The lower edge of the lever arm 40 is provided with a surface portion 40b that engages the interior surface of the arm bracket 12 when the actuating means is in inactive position. A link 41 has its opposite ends pivotally connected respectively to the lever arm 36 and the lever arm 40. An adjusting handle 42 is secured to the right hand end of the adjusting shaft 34 to actuate said shaft, it being noted that a bowed spring 43 is interposed between the handle 42 and the arm bracket of the machine and acts to hold the handle and the shaft in any position to which they have been adjustably rocked.

When the handle 42 is in the position shown in Fig. 4 the eccentric pin 39 is so located that the lever arm 40 is drawn toward the right and downwardly to the position shown in Fig. 4, at which time the surface 40b of the lever arm is in

engagement with the interior surface of the arm bracket 12 and the link 41 has been moved by the lever arm 40 to move the lever arm 36 to the position shown in Fig. 4 and hold the latter therein, at which time the upward travel of the roller 27 with the needle bar 14 will not impart any appreciable movement to the lever arm 36. When the handle 42 is moved from the position shown in Fig. 4 toward the position shown in Fig. 5 the eccentric pin 39 moves as the shaft 34 is rocked and shifts the lever arm 40 toward the left as viewed in the drawings, and such shifting movement of the lever arm 40 acts through the link 41 to draw or pull the lever arm 36 toward the needle bar 14 and more fully into the path of the roller 27. Therefore the roller 27 as the needle bar moves upwardly acts on the surface 36a of the lever arm 36 and rocks said arm to the right a substantial distance with the result that the link 41 pulls upwardly on the lever arm 40 and causes the curved protuberance 40a thereof to engage with and lift the block 25 against the action of the spring 23 with a resultant lifting of the presser bar and presser foot.

From the foregoing description it will be seen that the actuating means in this modified form can be rendered inactive when the machine is performing ordinary sewing operations but by simple movement of the lever 42 can be rendered active for lifting the presser bar on each up stroke of the needle bar and therefore the machine can be used for darning operations. It will also be noted that a range of active adjustments can be imparted to the actuating mechanism wherefore the amplitude of lift given to the presser bar can be varied in accordance with the thickness of the material upon which the darning operation is being performed.

Although several preferred embodiments of the invention have been illustrated and described herein it should be understood that the invention is susceptible of various modifications and adaptations within the scope of the appended claims.

Having thus described my invention I claim:

1. In a sewing machine adapted to function selectively for ordinary sewing operations or for darning operations, a reciprocating needle bar, a presser bar normally spring pressed in a downward direction, a member mounted for rocking movement on a shiftable axis, means for shifting said axis selectively to either one of two positions, and means forming an operative association between said member and said needle bar and between said member and said presser bar only when said axis is shifted to one of said two positions.

2. In a sewing machine adapted to function selectively for ordinary sewing operations or for darning operations, a reciprocating needle bar having thereon an actuating element, a presser bar normally spring urged in a downward direction and having thereon an abutment portion, a lever arm mounted for rocking movement on a shiftable axis and having at its free end a portion adapted to engage said abutment portion when said lever arm is rocked upwardly, means for shifting said axis selectively to either one of two positions, and means effective only when said axis is in one of said two positions for operatively associating said lever arm with said actuating element wherefore upward movement of said needle bar effects upward rocking movement of said lever arm and in turn upward movement of said presser bar.

3. In a sewing machine adapted to function selectively for ordinary sewing operations or for darning operations, a reciprocating needle bar having thereon an actuating element, a presser bar normally spring urged in a downward direction and having thereon a lifting block, a member mounted for rocking movement on a shiftable axis and having a portion adapted when said member is rocked upwardly to engage said block and lift said presser bar, a lever arm operatively connected with said member and having an upwardly extending portion provided with an actuating surface adapted to cooperate with said element during reciprocation of said needle bar to rock said arm and member, and means for shifting said axis of said member to dispose said lever arm and the actuating surface thereof in either an inactive position relative to said element or in an active position relative thereto.

4. In a sewing machine adapted to function selectively for ordinary sewing operations or for darning operations, a reciprocating needle bar having mounted thereon an actuating element, a presser bar normally spring urged in a downward direction and having thereon a lifting block, a rockable shaft having an eccentric portion, a lever mounted on said portion for rocking movement and having its free end underlying said lifting block on said presser bar, a lever arm operatively connected to said lever and having its upper end located adjacent to said actuating element, and means for rocking said shaft to shift said eccentric portion and the axis of rocking movement of said lever and to move said lever arm either to a position wherein said actuating element acts on said arm during upward movement of the needle bar to rock said arm and said lever or to a position wherein said element is inactive with respect to said lever arm.

5. In a sewing machine adapted to function selectively for ordinary sewing operations or for darning operations, a reciprocating needle bar having mounted thereon an actuating element, a presser bar normally spring urged in a downward direction and having thereon a lifting block, a rockable shaft having an eccentric portion, a lever mounted on said portion for rocking movement and having its free end underlying said lifting block on said presser bar, a lever arm operatively connected to said lever and having its upper end located adjacent to said actuating element, and means for rocking said shaft to shift said eccentric portion and the axis of rocking movement of said lever and to move said lever arm either to a position wherein said actuating element acts on said arm during upward movement of the needle bar to rock said arm and said

lever and raise said block and presser bar or to a position wherein said element is inactive with respect to said lever arm, and means for holding said shaft in any position to which it is rocked.

6. In a sewing machine adapted to function selectively for ordinary sewing operations or for darning operations, a reciprocating needle bar provided with a roller, a presser bar normally spring urged in a downward direction and provided with a lifting block, a rockable shaft extending transversely to said needle bar and presser bar and provided with an eccentric portion, a bell crank lever mounted on said eccentric portion at the junction of its angularly disposed arms, one of said arms being provided at its free end with means adapted to engage said lifting block of said presser bar, the other of said arms being provided adjacent its free end with an actuating surface adapted to cooperate with said roller during reciprocation of said needle bar, an actuating member for rocking said shaft to shift said eccentric portion and the axis of said bell crank lever to a position wherein said roller is inactive with respect to said actuating surface or to a position wherein said roller contacts said actuating surface and rocks said lever during upward movement of said needle bar to cause the first named arm of the lever to engage said lifting block and raise said presser bar.

7. In a sewing machine adapted to function selectively for ordinary sewing operations or for darning operations, a reciprocating needle bar having thereon a roller, a presser bar normally spring urged in a downward direction and having thereon a lifting block, a rockable shaft extending transversely to said needle bar and having an eccentric portion, a lever mounted on said eccentric portion and having its free end underlying said lifting block, an upwardly extending lever arm rockably mounted on said shaft concentrically therewith and having at its end an actuating surface located adjacent to said roller, a link pivotally connected to said lever and said lever arm, and means for rocking said shaft to shift said eccentric portion and the axis of rocking movement of said lever to swing said lever arm through said link into a position where the actuating surface thereof will lie in the path of movement of said roller whereby said lever arm, link and lever will be rocked by said roller during upward movement of said needle bar to cause said lever to engage said lifting block and raise the presser bar or to a position wherein said roller is inactive with respect to said actuating surface of the lever arm.

CHARLES E. COLEGROVE.
